D11-148.

OR D11,596 EX

Design No. 11,596, dated January 13, 1880.

UNITED STATES PATENT OFFICE.

FRANK H. SHEPHERD, OF BOSTON, ASSIGNOR TO JAMES W. TUFTS, OF MEDFORD, MASSACHUSETTS.

DESIGN FOR HOLDERS FOR FLOWERS, MATCHES, &c.

SPECIFICATION forming part of Design No. 11,596, dated January 13, 1880.

Application filed December 10, 1879. Term of patent 3½ years.

To all whom it may concern:

Be it known that I, FRANK H. SHEPHERD, of Boston, in the county of Suffolk and State of Massachusetts, have invented and produced

5 a new and original Design for a Holder for Flowers, Matches, &c., of which the following is a full, clear, and exact description, reference being had to the accompanying photograph, making part of this specification.

10 This invention consists in a design for a holder for flowers, matches, &c., to be used as an ornament for tables, mantel-pieces, &c.

15 In the photograph, A is a base, representing the ground, rising from which is a rustic frame or support, B, consisting of two upright pieces, a a, and two upwardly-inclined pieces, b b, from which depends a chain, c, attached to a kettle, C, the kettle serving as a holder for flowers, matches, &c., a beautiful and unique design being thus produced.

20

What I claim as my invention, and desire to secure by Letters Patent, is—

The design for a holder of flowers, matches, &c., consisting of the kettle C, hung within the frame B, rising from the base A, substantially as herein shown and described.

25 Witness my hand this 6th day of December, A. D. 1879.

FRANK H. SHEPHERD.

In presence of—

P. E. TESCHEMACHER,
W. J. CAMBRIDGE.
